UNITED STATES PATENT OFFICE

ARTHUR C. MATTISON, OF EAU CLAIRE, WISCONSIN

DESIGN FOR A CIGAR AND CIGARETTE HOLDER

Application filed December 19, 1931. Serial No. 42,150. Term of patent 7 years.

To all whom it may concern:

Be it known that I, ARTHUR C. MATTISON, a citizen of the United States, and a resident of Eau Claire, in the county of Eau Claire and State of Wisconsin, have invented a new, original, and ornamental Design for a Cigar and Cigarette Holder, of which the following is a specification, reference being had to the accompanying drawing, forming part thereof.

The figure is a side elevational view of the combined cigar and cigarette holder showing essentially the outline of the lower part of a leg and foot, the same being hollow and adapted to receive a cigar or cigarette in the severed leg end thereof.

I claim:

The ornamental design for a cigar and cigarette holder as shown and described.

In testimony that I claim the foregoing I have hereunto set my hand at Eau Claire, in the county of Eau Claire and State of Wisconsin.

ARTHUR C. MATTISON.
